UNITED STATES PATENT OFFICE.

EMIL GEISEL, OF BARNES, LONDON, ENGLAND, ASSIGNOR TO GENERAL ELECTRIC COMPANY, A CORPORATION OF NEW YORK.

METALLIC-FILAMENT INCANDESCENT ELECTRIC LAMP.

1,223,958.

Specification of Letters Patent. Patented Apr. 24, 1917.

Application filed October 8, 1912. Serial No. 723,674.

To all whom it may concern:

Be it known that I, EMIL GEISEL, a subject of the Emperor of Germany, residing at Barnes, London, England, have invented certain new and useful Improvements in Metallic-Filament Incandescent Electric Lamps, of which the following is a specification.

The present invention relates to metallic-filament electric lamps with the illuminating body carried back and forth over the retaining parts of a supporting frame.

Incandescent electric lamps are already known, in which the illuminating body is placed zigzag upon the holders which are arranged in parallel planes upon a common supporting stem; in these cases the illuminating body is carried over books provided at the supporting-ends of the holders.

This construction, however, has the disadvantage that the illuminating body may be disengaged from the slender elastic holders commonly employed on the end of the supporting stem that is farthest away from the base, when very severe shocks occur in the direction of said supporting stem. The above occurrence may be due to the fact that the elastic holders are weighted beyond their limit of elasticity, so that they become permanently distorted.

It is a practice already known to proceed in the application of the illuminating body in such manner that the hook-like supporting parts, after the illuminating body is put in place, are bent so as to form a closed eye, whereby the danger of the illuminating body's slipping from the holders is almost obviated, but this process requires special manipulation after the filament is applied, which manipulation under some circumstances may endanger the illuminating body.

The disadvantages above set forth are avoided by the present invention which may be understood from the following description taken in connection with the attached drawings, in which Figure 1 shows an embodiment of my invention in a complete lamp; Fig. 2 shows an enlarged view of a support; Fig. 3 shows a section through the coil near its contact with the filament, and Fig. 4 shows a modification in which the support is given a number of helical turns. By reference to the drawings, it will be seen that the supporting ends of the practically rigid holders 1-1, which are near the base,

are made in the form of helical eyes 2, 2 and are turned toward the elastic holders 6-6 as shown in Figs. 1 and 2, while the elastic holders are provided with hooks 3, 3 in the ordinary manner. The eyes 2-2 60 permit a more convenient and more secure location of the lighting body 4, and at the same time prevent the lighting body from sliding off the rigid holders. Moreover, the movement of the sections of the lighting 65 body, which is caused by an axial shock directed toward the base is limited not merely by one, but by two, points of support as shown at 2 and 5 in Fig. 3, so that the elastic holders are relieved with greater certainty. In order to represent this effect, a section through the eye is shown in Fig. 3, and the corresponding curve of the bight of the lighting body is represented not only in normal position, but it is also shown in dotted lines in the position which it assumes when it receives a blow.

According to the modification shown in Fig. 4 the ends of the substantially rigid holders adjacent to the socket are provided 80 with a number of helical turns 7-7, three being shown in this instance, and the illuminating body 4 is so arranged in one of the turns, say the middle one, that on both sides of the bight of the illuminating 85 body other turns are provided which afford additional points of contact in case of axial shock and also increased security against the slipping off of the illuminating body from the holders. In this modification the coiled end of the supports is turned away from the flexible supports. By the use of the present invention, the filament can be applied rapidly and without drawing it through an eye, while at the same 95 time, all the advantages of the closed eye are obtained. The same is true of the structure shown in the other figures.

What I claim as new and desire to secure by Letters Patent of the United States, is:— 100

1. In an incandescent lamp, the combination of a central supporting stem, a plurality of sets of supports mounted thereon, the members of one set being flexible and having hooks on the ends thereof, the members 105 of another set being comparatively rigid and having an open coil in the outer end thereof, a continuous refractory filament strung back and forth between the members of the sets of supports so that the axial movement 110

of the filament in the direction of the rigid supports is limited by the coiled portion in the rigid support.

2. In an incandescent lamp, a central sup-

porting stem, a plurality of hooked flexible supports mounted thereon, a plurality of rigid supports mounted thereon, said rigid supports having a helical coil on the end thereof, and a continuous filament strung back and forth between said supports and capable of longitudinal movement with respect to the rigid supports, the filament being arranged to engage the rigid support at one point under normal conditions and at 15 a plurality of points under abnormal conditions.

3. In an incandescent lamp, a central supporting stem, a hooked flexible support mounted thereon, a rigid support mounted 20 thereon, said rigid support having a helical coil on the end thereof, said coil con-

sisting of more than one turn, a continuous filament strung back and forth between said flexible and rigid support, said filament normally engaging one spire of said coiled portion of the rigid support and engaging two adjacent spires of said coil on movement caused by abnormal conditions. ²⁵

4. The combination in an incandescent lamp of a filament support having a helical coil on the end thereof, said coil consisting of more than one turn and a filament normally engaging one spire of said coiled portion and engaging two adjacent spires under abnormal conditions. ³⁰

In witness whereof, I have hereunto set my hand this 16th day of Sept., 1912. ³⁵

EMIL GEISEL.
